CLAIM

The ornamental design for a monitor, as shown and described.

DESCRIPTION

FIG. 1 is a front top perspective view of a monitor, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear bottom perspective view thereof; and,

FIG. 9 is an enlarged view of the portion 9 in FIG. 1.

Even-dash broken lines depict portions of the monitor that form no part of the claimed design. Dot-dot-dash broken lines represent the boundary of the enlarged portions and form no part of the claimed design.

1 Claim, 9 Drawing Sheets
